ABSTRACT

A filled, biaxially oriented, void-containing thermoplastic film suitable for making heat-shrinkable bands is provided having shrinkage on heating to 100° C. of

greater than 5%, which shrinkage in turn is at least 5% greater than the shrinkage in a direction perpendicular thereto.

A process for preparing this film with its preferential shrinkage is provided including the steps of:

- (a) melt-blending a C₂-C₁₀ α -monoolefin polymer and at least 20 weight percent inert filler, based on the total weight of polymer and filler;
- (b) forming a film from the melt blend;
- (c) cooling the film to a temperature below the melting point;
- (d) biaxially stretching the film at least about twice its original forming dimensions in mutually perpendicular directions while the film temperature is above the line-drawing temperature and below the polymer melting temperature, until the film has at least about 30% voids;
- (e) cooling the film to room temperature; and
- (f) post-stretching the biaxially stretched film in a selected direction at a temperature below 100° C. to an extent that provides the above-mentioned preferential shrinkage in the filled film.
